UNITED STATES PATENT OFFICE

HERMAN SCHWARTZ, OF PHILADELPHIA, PENNSYLVANIA, ASSIGNOR TO APACA KNITTING MILLS, OF PHILADELPHIA, PENNSYLVANIA, A CORPORATION OF PENNSYLVANIA

COLLAR FOR SWEATERS AND METHOD OF MAKING THE SAME

Application filed April 23, 1930. Serial No. 446,430.

This invention relates to an improved construction of a collar for sweaters of the type without a front opening and in which, as a result, the collar is in the form of a permanently closed band.

Heretofore such collars have been made from strips of knitted material having their ends folded and stitched together to form a pointed front, so that the collar was of the ordinary V-neck type. The resultant seam in the front of the neck opening resulting from this construction is the weakest part of the sweater and usually breaks under the strains incident to the stretching of the collar to permit the passage therethrough of the head of the wearer.

It is the primary object of the invention to provide a collar of knitted construction throughout without stitched seams liable to rupture upon the application of strains to the collar.

It is a further object to provide a collar which naturally assumes the proper shape when the sweater is worn as compared with the distortion of the ordinary collar when the sweater is worn.

Another object relates to the production of a new design in the collar of a type impossible in the ordinary construction.

Further objects relating to details of construction and advantageous methods of construction will be apparent from the following description read in conjunction with the accompanying drawings in which:

Fig. 1 is an elevation of the upper front portion of a sweater showing the improved collar;

Fig. 2 is a fragmentary inside view of the lower front portion of a modified form of collar and adjacent parts of the sweater body;

Fig. 3 illustrates diagrammatically the formation of the finished seam between the collar and sweater body;

Fig. 4 is a plan view of a knitting mecha-

nism illustrating the position of the fabric at the beginning of the formation of the central section of the collar;

Fig. 5 is an enlarged view of the central portion of Fig. 4; and

Fig. 6 is a diagrammatic view illustrating steps of the method of making the collar.

A knitted sweater is indicated at 2 to the neck of which is secured the collar, which consists of the band section 4 and the tapered connecting section 6. The collar is secured to the sweater about its edges by any suitable seam, of which a preferred form is illustrated in Fig. 3, there being shown in that figure the three steps in its formation. A tape 8 is stitched as indicated to the collar 4 and the body 2 of the sweater by straight stitches 10, the tape being then folded over the seam and secured at its other edge to the body of the sweater by blind overseaming stitches 12. This method of procedure provides a finished seam on the inside of the sweater and there is also presented a smooth junction of the collar to the body of the sweater on the outside.

As distinguished from the type of knitted collar heretofore provided which contains a stitched seam, the present collar is knitted throughout. Its construction will best be understood by a reference to a preferred method of forming it.

Referring to Fig. 4, there is diagrammatically illustrated a series of opposed staggered needles together with the sinkers of an ordinary flat knitting machine arranged to produce either ribbed or tubular work. In Fig. 4, two central needles are designated as *a*, the successive needles on one side being designated as *b*¹, *b*², ..., *b*ⁿ, and the needles on the other side being designated as *c*¹, *c*², ..., *c*ⁿ. In starting the collar the needles *c*¹ to *c*ⁿ are idle, several courses of tubular fabric being formed upon the needles *a*, *b*¹, *b*², ..., *b*ⁿ. This tubular portion, which is indicated in a later stage in Fig. 4, is indicated at 14. After the

production of these several courses, the machine is arranged to form a ribbed portion designed 16, this operation being continued until the desired length of band is produced.

5 The last ribbed course is indicated at 18, the loops being carried by the needles $a, b^1, \dots b^n$.

The loops of one of the tubular courses 14, which are now hanging free, are brought, as indicated in Fig. 6, up to the needles which 10 where heretofore idle, the loops being placed upon the needles a, c^1, c^2, c^n . It will be noted that the two end loops of the course 14 are placed over the same needles a which contain the two adjacent end loops of the course 18.

15 The machine is then arranged for tubular knitting which is carried out for a series of courses on all of the needles heretofore mentioned, namely, from b^n to c^n . Preferably the connecting section 6 is tapered, as indicated 20 in Fig. 1, and therefore fashioning is produced by taking the loops from the end needles after a predetermined number of courses and displacing them inwardly on other needles, the empty needles being then thrown out 25 of operation. This fashioning is, of course, of the general type produced on this sort of machine. Preferably the fashioning is carried to such an extent that the tapered edges 30 of the connecting portion 6 are substantially continuous with the outer side edges of the band section when the collar is placed on a sweater. The end of the connecting section is secured in any desired and usual fashion.

From the above description the appearance 35 of the finished collar will be apparent. The band portion 4 is, in the main, ribbed, the ribbed construction being preferred by reason of the fact that each reciprocation of the thread carrier on the machine produces a complete course, with a saving of yarn. There 40 may be one or two courses of tubular portion, as mentioned above, directly connected to the connecting section. Preferably the extent of the tubular portion of the band 4 is minimized. If the yarns used in the band and 45 connecting sections are the same, a junction is produced which can only be distinguished with difficulty. The overlapping of the loops at the needles a produces added strength at 50 the point where the greatest strain occurs during the use of the sweater. There is thus eliminated any tendency of the collar to open at the front. The construction just described furthermore produces a collar the portions of 55 which tend to lie flat upon the body of the wearer, since there is no distortion as ordinarily occurs in the type of band heretofore used and described above, provided with a 60 stitched seam at its front central portion.

An alternative modification which produces an attractive appearance is indicated in Fig. 2, in which a different color yarn is used in the section 6', as compared with that used in 65 the band section 4. A triangular insert of

contrasting color is thus produced, a design not obtainable in collars of the old type.

While there has been described above a preferred form of the invention and method of producing the same, it will be obvious that 70 numerous variations may be made without departing from the spirit of the invention. For example, while a tubular portion 14 is preferably formed initially, this is done only to facilitate the introduction of the loops 75 upon the needles at the time when the connection section is about to be secured to the band section. The band section could be wholly ribbed or wholly tubular, or even flat knitted if the method were carried out on a 80 different type of machine. The preferred method provides both ease of manipulation and saving of yarn. Likewise the connecting section 6 might be ribbed instead of tubular. It is preferably made tubular, since the transfer of loops for fashioning is thereby facilitated.

Instead of knitting the connecting section to the band section as described above, certain advantages of the invention may be retained if the ends of the band section are connected to the connecting section by stitches, for example, overseaming stitches. With this construction, even though stretching does occur, it is not subjected to the great strains 90 to which the stretching in the ordinary form of collar is subjected. At the same time the advantage of the proper shaping of the collar is retained. On the other hand, this form is not quite so good as the entirely knitted 95 form which produces a more homogeneous and better appearing product.

Other variations of the invention will be apparent within the scope of the following claims.

What I claim and desire to protect by Letters Patent is:

1. A continuous knitted collar for a sweater including an elongated knitted band section and a front knitted connecting section, the connecting section tapering downwardly and having a top approximately double the width of the band section, the ends of the band section being joined to the respective sides of the top of the connecting section.

2. A continuous knitted collar for a sweater including an elongated knitted band section and a front knitted connecting section, the connecting section tapering downwardly and having a top approximately double the width of the band section, the ends of the band section being joined to the respective sides of the top of the connecting section, and the tapering edges of the connecting section being continuous with the outer side edges of the band section.

3. A continuous knitted collar for a sweater including an elongated knitted band section and a front knitted connecting section, the connecting section being fashioned to taper 130

sweater including an elongated band section and a front connecting section, the band section being ribbed and having wales extending longitudinally thereof, and the connecting section being tubular knit and having downwardly extending wales and being fashioned to taper downwardly, loops at one end of the band section being interlinked with loops along one side of the top of the connecting section, and loops at the other end of the band section being interlinked with loops along the other side of the top of the connecting section, the tapering edges of the connecting section being continuous with the outer side edges of the band section.

14. A continuous knitted collar for a sweater including an elongated band section and a front connecting section, the band section being ribbed and having wales extending longitudinally thereof, and the connecting section being tubular knit and having downwardly extending wales and being fashioned to taper downwardly, its top being approximately double the width of the band section, loops at one end of the band section being interlinked with loops along one side of the top of the connecting section, and loops at the other end of the band section being interlinked with loops along the other side of the top of the connecting section, there being loops at the center of the connecting section, interlinked with loops of both ends of the band section, the band section and connecting section being of contrasting appearance, the tapering edges of the connecting section being continuous with the outer side edges of the band section.

15. The method of forming a collar for sweaters including knitting an elongated band section, bringing the ends of the band section in alignment, and knitting a connecting section to the ends by forming loops interlinked with loops on both ends of the band section.

16. The method of forming a collar for sweaters including knitting an elongated band section, bringing the ends of the band section in alignment, knitting a connecting section to the ends by forming loops interlinked with loops on both ends of the band section, and fashioning the connecting section to taper from its junctions with the ends of the band section.

17. The method of forming a collar for sweaters including knitting an elongated band section with an initial tubular portion followed by a main ribbed portion, bringing the free end of the tubular portion into alignment with the free end of the ribbed portion, and knitting a tubular connecting section to the ends by forming loops interlinked with loops on both ends of the band section.

18. The method of forming a collar for sweaters including knitting an elongated band section with an initial tubular portion

followed by a main ribbed portion, bringing the free end of the tubular portion into alignment with the free end of the ribbed portion, knitting a tubular connecting section to the ends by forming loops interlinked with loops on both ends of the band section, and fashioning the connecting section to taper from its junctions with the ends of the band section.

In testimony of which invention, I have hereunto set my hand, at Philadelphia, Pennsylvania, on this 11th day of April, 1930.

HERMAN SCHWARTZ.
